NECK AND FACIAL TONER

Jack Vincent Feather, 11293 Kerrigan Drive,
Oakland, Calif. 94605

Filed Aug. 29, 1966, Ser. No. 3,640

Term of patent 14 years

(Cl. D83—1)

Fig. 1

Fig. 2

Fig. 3

FIGURE 1 is a perspective view of the neck and facial toner;

FIGURE 2 is a side elevation view of the neck and facial toner;

FIGURE 3 is a front elevation view of the neck and facial toner;

FIGURE 4 is a rear view of the neck and facial toner;

FIGURE 5 is a bottom plan view of the neck and facial toner taken along lines 5—5 of FIGURE 4;

FIGURE 6 is a sectional view of the neck and facial toner taken along lines 6—6 of FIGURE 4.

The dominant features of my design reside in the portion shown in full lines.

I claim:

The ornamental design for a neck and facial toner, as shown and described.
